Patented Jan. 19, 1971

219,753

FINGERPRINT COMPARISON APPARATUS

Stephen Roka, 30 Goshen Court,
Gaithersburg, Md. 20760

Filed June 3, 1969, Ser. No. 17,498

Term of patent 14 years

Int. Cl. D16—03

U.S. Cl. D52—1

Fig. 1

Fig. 2

Fig. 3

FIG. 1 is a perspective view of the fingerprint comparison apparatus;

FIG. 2 is a top plan view; and

FIG. 3 is an end view.

The undisclosed rear side is unornamental.

I claim:

The ornamental design for a fingerprint comparison apparatus, as shown and described.
